UNITED STATES PATENT OFFICE

GEORGE S. LAIRD, OF PHILADELPHIA, PENNSYLVANIA, ASSIGNOR TO LAIRD, SCHOBER & CO., OF PHILADELPHIA, PENNSYLVANIA, A FIRM COMPOSED OF GEORGE S. LAIRD, J. LAIRD SCHOBER, JOHN C. McKEON, AND SAMUEL S. LAIRD, JUNIOR

DESIGN FOR A SHOE VAMP

Application filed November 6, 1931. Serial No. 41,638. Term of patent 3½ years.

To all whom it may concern:

Be it known that I, GEORGE S. LAIRD, a citizen of the United States, residing in Philadelphia, Pennsylvania, have invented a new, original, and ornamental Design for a Shoe Vamp, of which the following is a specification, reference being had to the accompanying drawing, forming part thereof, in which the figure is a plan view of a shoe vamp showing my new design.

The dominant feature of my design resides in the ornamental embossed background produced by bands of multiple cross-stitching so arranged as to leave substantially diamond-shaped spaces therebetween.

I claim:

The ornamental design for a shoe vamp substantially as shown and described.

GEORGE S. LAIRD.
